2 Sheets-Sheet 1

Fig. 1. A technical drawing of a mechanical device. The top part shows a horizontal beam 12 supported by two vertical columns 5. A vertical handle 7 with a grip 8 is attached to the left column 5. A horizontal rod 6 is attached to the right column 5. Two vertical plates 11 are positioned between the columns, each with a slot 25. A horizontal beam 14 is supported by two vertical columns 1. A horizontal beam 51 is supported by two vertical columns 4. The bottom part shows a rectangular base structure with vertical supports and horizontal beams.

FIG. 2. A vertical assembly of mechanical parts. It includes a base plate (1), a vertical frame (2), a central vertical rod (3), a horizontal rod (4) attached to a gear (5), a chain (6) connecting the gear to a pulley (7), a vertical chain (8) attached to the pulley, a vertical plate (9) with a circular opening, and a horizontal plate (10) with a circular opening. A vertical chain (11) is attached to the top of the vertical plate and hangs down. A horizontal chain (12) is attached to the top of the horizontal plate and hangs down. A vertical plate (13) is attached to the bottom of the vertical frame. A horizontal plate (14) is attached to the bottom of the horizontal frame. A vertical plate (15) is attached to the bottom of the vertical frame. A horizontal plate (16) is attached to the bottom of the horizontal frame.

FIG. 3. A vertical assembly of mechanical parts. It includes a base plate (1), a vertical frame (2), a central vertical rod (3), a horizontal rod (4) attached to a gear (5), a chain (6) connecting the gear to a pulley (7), a vertical chain (8) attached to the top of the vertical frame and hanging down, a horizontal chain (9) attached to the top of the horizontal frame and hanging down, a vertical plate (10) attached to the bottom of the vertical frame, and a horizontal plate (11) attached to the bottom of the horizontal frame.

UNITED STATES PATENT OFFICE

WILLIAM BECHER, JR., OF YOUNGSTOWN, NORTH DAKOTA

HOG SCALDER

Application filed April 18, 1928. Serial No. 270,970.

This invention relates to means for facilitating the scalding of hogs, the general object of the invention being to provide means for supporting and turning a hog in the scalding tank and to remove the hog from the tank upon a table when the scalding operation is completed.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is a side view of the invention.

Figure 2 is an end view thereof.

Figure 3 is a section on line 3—3 of Figure 1.

Figure 4 is a section on line 4—4 of Figure 2, and showing the device in use.

Figure 5 is a sectional view showing how the device is used to lift a hog from the tank upon the table.

Figure 6 is a perspective view of a pair of connected links of the chains.

In these views, the numeral 1 indicates the scalding tank and 2 indicates a table hingedly connected with one side of the tank, as shown at 3, and having a pair of legs 4 hingedly connected thereto. A pair of uprights 5 is fastened to the tank, one at each end thereof and a shaft 6 is journaled in the upper ends of these uprights. One end of the shaft is provided with a handle 7 which carries a ratchet 8 engaged by a dog 9 carried by the upright for holding the shaft against retrograde movement.

A pair of sprockets 10 is fastened to the shaft in spaced relation and an endless chain 11 passes over each sprocket and depends into the tank. Some of the links of the chains are connected together by the angle pieces 12 and the links of each chain are detachably connected together by the hooks 13, though if desired, but two of the links of each chain may be detachably connected together in any

suitable manner. A pair of hooks 14 is fastened to the upper face of the table adjacent its inner edge.

The hog to be scalded is placed on the table and the chains passed around the body of the hog. This may be done by attaching one link of each chain from its adjacent link so that the chain may be placed around the hog and then the links are fastened together again. The hog is then placed in the tank and this may be done by rotating the shaft to cause the chains to pull the hog from the table into the tank. The shaft is turned by means of its handle to roll the hog in the scalding water and then after the hog has been scalded, some of the links of the chains are detached from their adjacent links and placed in engagement with the hooks 14. Then the shaft is again rotated to cause the chains to pull the hog from the tank on to the table, where the scraping operation may be carried out. By making the table foldable, it may be swung downwardly against the sides of the tank when not in use, and in this position, a link of each chain may be placed over the hooks 14 so that the table will be automatically raised when the shaft is turned to lift the hog from the tank on to the table. The angle cross pieces 12 act to prevent the hog slipping on the chains.

It is thought from the foregoing description that the advantages and novel features of the invention will be readily apparent.

It is to be understood that I may make changes in the construction and in the combination and arrangement of the several parts, provided that such changes fall within the scope of the appended claims.

What I claim is:

1. A device of the class described comprising a tank, uprights connected with the ends of the tank, a shaft journaled in the uprights, a handle on the shaft, sprocket wheels on the shaft, endless chains passing over the wheels and depending into the tank for supporting a hog in the tank and for turning the hog when the shaft is turned, a table hingedly connected with one side of the tank, foldable legs on the outer edge of the table and hooks on the table for receiving a link of each chain.

after said link has been detached from the adjacent link to cause the chains to pull the hog from the tank and roll it upon the table when the shaft is turned.

5 2. A device of the class described comprising a tank, uprights connected with the ends of the tank, a shaft journaled in the uprights, a handle on the shaft, sprocket wheels on the shaft, endless chains passing over the wheels and depending into the tank for supporting 10 a hog in the tank and for turning the hog when the shaft is turned, a table at one side of the tank and hooks on the table for receiving a link of each chain after said link has 15 been detached from the adjacent link to cause the chains to pull the hog from the tank and roll it upon the table when the shaft is turned.

In testimony whereof I affix my signature.

WILLIAM BECHER, Jr.
